DESIGN FOR A COMBINED PEDESTAL AND HOUSING FOR HAIR DRIERS OR SIMILAR MACHINES

John E. Kelley, Larchmont, N. Y.

Application February 23, 1934, Serial No. 50,828

Term of patent 7 years

To all whom it may concern:

Be it known that I, JOHN E. KELLEY, a citizen of the United States of America, residing in Larchmont, county of Westchester, State of New York, have invented a new, original and ornamental Design for a Combined Pedestal and Housing for Hair Driers or Similar Machines, of which the following is a specification, reference being had to the accompanying drawing forming part thereof.

Fig. 1 is a front perspective view of a combined pedestal and housing for a hair-drier showing my new design.

Fig. 2 is a top plan view thereof.

I claim:—

The ornamental design for a combined pedestal and housing for a hair drier or similar machine substantially as shown.
